UNITED STATES PATENT OFFICE

2,431,939

ABRADING MACHINE

Franklin D. Johnson, Battle Creek, Mich.

Application August 11, 1945, Serial No. 610,221

4 Claims. (Cl. 51—128)

1

This invention relates to a device for sharpening and polishing cutlery and has for an object to provide means for sharpening knives and the like and means whereby the same may be polished.

Another object of the invention is to provide an abrader and means for mechanically holding cutlery to be sharpened against the same.

A further object of the invention is to provide means whereby a plurality of knives or the like may be sharpened at one time.

A still further object of the invention is to provide in an abrader a reciprocable cutlery holder.

Another object of my invention is to provide in a grinding machine resilient means whereby a plurality of knives or the like may be held slidably moved against an emery wheel or the like.

And another object of the invention is to provide in a machine of the above mentioned character means for driving a polishing brush or the like.

Other features and advantages will become more readily apparent from the following description and the accompanying illustrative drawings in which:

Figure 1 is a vertical sectional view of my machine, a carriage being removed,

Figure 2 is a top plan view of the carriage,

Figure 3 is a side elevational view thereof, and

Figure 4 is a sectional view taken on line 4—4 of Figure 2, and

Figure 5 is a detail of a knife supporting member and emery wheel.

In the drawings and in the specification the same reference characters are used to indicate like parts throughout and in which 10, refers to my knife sharpening machine, consisting of a frame 11, which includes an elongated bearing 12, for a spindle 13, projecting at one end 14, into an oil tight housing 15, and at the other end into an oil sump 16. The wall 17, of housing 15, is provided with an extending hub 18, adapted to be fixedly attached to the shaft 19, of a sausage machine, or any other driven machine or directly to a motor shaft (not shown) as indicated at 20, by means of the head 21, of the shaft 22, operating in the hub and projecting into housing 15, as at 23, and fixedly mounted on said part 23, is a large gear wheel 24, meshed with a pinion gear 25, fixed on said end 14, of spindle 13.

Fixed on the end 26, of said spindle 13, is a large gear wheel 27, geared to a pinion 28, splined on shaft 29, supported in the bearings 30 and 31, forming a part of the frame 11. Also splined on the ends 32 and 33, of the shaft 29, are a pair of

2

spaced emery wheels 34 and 35, having tapering outer peripheral portions 36 and 37, the purpose of which will presently be explained. The bearing members 30 and 31, support a table 38, having slots 39 and 40, through which the emery wheels project. Projecting up from each side of each wheel are pivot pins 41, 42 and 43 and 44, all of which are located beyond said wheels and will be mentioned again.

10 The frame 11, includes the housing 15, with its removable wall 47, and the sump 16, with its removable wall 48. Attached to the under wall of the table 38, are housing guards 49 and 50, for the wheels 34 and 35. The extreme outer end 51, 15 of shaft 29, is splined and projects through an aperture 52, in the guard 50, which end is adapted to have a polishing wheel or buffer (not shown) attached thereto. A guard hood 53, is provided for said end 51, when not in use. The frame 20 structure 11, is provided with a bracing web 54.

A knife holder 55, comprises an elongated base 56, with one end 57, tapering and provided with a bore 58, adjacent its terminal 59, the purpose of which is to engage one of the said pins 43 to 25 46, and its other narrowed end 60, terminates in a downwardly inclined handle 61. Between said reduced ends 57 and 60, the longitudinal sides of the base are turned up to provide angularly disposed flanges 62 and 63, which are rigid. Intermediate of these flanges is a vertically disposed fixed wall 64, terminating in pins 65 and 66, upon which are pivoted the wings 67 and 68, and 69 and 70, of the longitudinal walls 71 and 72, which are slightly spaced from the fixed flanges 62 and 63, respectively and which together form slots 73 and 74, within which knife blades 75 or 76, may be seated slidably. Springs 77 and 78, on one side and 79 and 80, on the other side are mounted between the wall 64, and said walls 71 and 72, whereby the latter walls are normally forced against said blades to press them (one at a time) against the opposite sides of one of the above referred to emery wheels bevels 36 or 37. The said wings 68, 70, etc., are provided with 40 horizontally disposed oval slots 70', through which the pins 65 and 66, project in order to permit of slight sliding movement of the walls 71 and 72, to provide the pressure of the knife edge against the emery wheel. A stop 81, is provided on the table, to limit the outer pivotal movement of member 56, away from either wheel 34 or 35, in order that the user of the device may not strike against the wheel not being used.

45 The walls 72 and 73 are provided with a series 50 of openings 82 and 83, etc., with struck in upper

and lower bearings 84 and 85, for pins 86 and 87, upon which rollers 88, 89, 90, 91, etc., are pivotally mounted and the peripheries 92 and 93, of which project slightly through the said walls 71 and 72, and into the slots 73 and 74, and upon which a knife seats whereby the knife may be moved back and forth in a slot without much frictional resistance.

The operation of the above described device is very simple. The end 57, of member 55, is mounted over any one of the pins 43 to 45, a knife blade is then placed in the slot 73 or 74, nearest one side of one emery wheel, then the handle 61 is moved toward the wheel with one hand of the operator until the desired pressure of the knife against the wheel is obtained, then with his other hand the knife is moved forward and back against the wheel until one side edge of the blade is sufficiently ground, then the knife holder is changed to the other side of the wheel, the knife changed to the opposite slot and the operation repeated. It is obvious that two operators may use the device at one and the same time.

It is thought that persons skilled in the art to which the invention relates will be able to obtain a clear understanding of the invention after considering the description in connection with the drawings. Therefore, a more lengthy description is regarded as unnecessary.

Changes in shape, size and rearrangement of details and parts such as come within the purview of the invention claimed may be resorted to, in actual practice, if desired.

Having now described my invention, that which I claim as new and desire to procure by Letters Patent is:

1. An abrading machine comprising in combination, a framework forming a housing and a table on said housing, said table being provided with a plurality of openings, a driving shaft and a driven shaft rotatably journaled in said housing, step-up gearing operatively connecting said shafts, a plurality of abrading wheels mounted on said driven shaft and each protruding through one of said openings, a plurality of upstanding pins on said table, and a knife holder, said holder comprising a U-shaped channel provided with an eye at one end thereof and forming a handle at its remaining end, an upstanding rib intermediate the sides of said channel, a movable wall between each of said sides and said rib, compression springs between said rib and each of said walls, and a plurality of rollers rotatably mounted on each of said walls, the knife being slidably receivable between said sides and said rollers, and said eye being removably engageable with said pins whereby said holder and said associated knife are adapted for selective coaction with each side of each of said wheels.

2. An abrading machine comprising in combination, a framework forming a housing and a table on said housing, said table being provided

with a plurality of openings, a driven shaft rotatably journaled in said housing, a plurality of abrading wheels mounted on said shaft and each projecting through one of said openings, means for rotating said shaft, and a knife holder attachable to said table and comprising a U-shaped channel and a pair of spring-pressed walls positioned in said channel adjacent the sides thereof, said channels and said walls coacting to form guides adapted to receive a knife.

3. An abrading machine comprising in combination, a framework forming a housing and a table on said housing, said table being provided with a plurality of openings, a driven shaft rotatably journaled in said housing, a plurality of abrading wheels mounted on said shaft and each projecting through one of said openings, means for rotating said shaft, and a knife holder attachable to said table and comprising a U-shaped channel, an upstanding rib intermediate the sides of said channel, a movable wall between each of said sides and said rib, and compression springs between said rib and each of said walls, said walls coacting with said channel to form guides adapted to slidably receive a knife.

4. An abrading machine comprising in combination a framework forming a housing and a table on said housing, said table being provided with a plurality of openings, a driven shaft rotatably journaled in said housing, a plurality of abrading wheels mounted on said shaft and each projecting through one of said openings, means for rotating said shaft, and a knife holder comprising a U-shaped channel adapted at one end thereof for removable attachment to said table and forming a handle at its remaining end, an upstanding rib intermediate the sides of said channel, a movable wall between each of said sides and said rib, compression springs between said rib and each of said walls, and a plurality of rollers rotatably mounted on each of said walls, said sides and said rollers constituting guides adapted to slidably receive a knife.

FRANKLIN D. JOHNSON.
